Primary Examiner — Khawaja Anwar*Assistant Examiner* — Taylor O Mortorff(74) *Attorney, Agent, or Firm* — Duane Morris LLP(57) **CLAIM**

The ornamental design for a portable glove dryer as shown and described.

DESCRIPTION

FIG. 1 is a perspective view of a portable glove dryer according to the present invention.

FIG. 2 is a front elevation view of the portable glove dryer of FIG. 1.

FIG. 3 is a rear elevation view of the portable glove dryer of FIG. 1.

FIG. 4 is a right side elevation view of the portable glove dryer of FIG. 1.

FIG. 5 is a left side elevation view of the portable glove dryer of FIG. 1.

FIG. 6 is a top plan view of the portable glove dryer of FIG. 1; and,

FIG. 7 is a bottom view of the portable glove dryer of FIG. 1.

The broken lines show portions of the portable glove dryer that form no part of the claimed design.
